UNITED STATES PATENT OFFICE

2,422,402

HUMIDIFIER FOR CARBURETERS

Antoine Gazda, Providence, R. I.

Application November 16, 1943, Serial No. 510,548

2 Claims. (Cl. 261—99)

1

The present invention relates to the cleaning and humidifying of the suction air of an internal combustion engine, and also to the intimate admixing and atomization of the air and entrained or added moisture.

Desiderata in apparatus for effecting the aforesaid operations are (a) that the air be as thoroughly cleaned as possible prior to humidification thereof and (b) that the admixture of air and moisture resulting from the humidification be as intimate and uniform as possible and in a high degree of atomization.

In the specification of my prior U. S. patent, No. 1,945,431, I have described a humidifier and air-filter for a carburetor of an internal combustion engine. The said humidifier consisted essentially of a multi-walled hollow member of cylindrical shape, constructed as a water or liquid receptacle, whose inner and outer walls were made of porous material. This water or liquid receptacle, filled with water or liquid, was connected with the suction inlet of the internal combustion engine. The air sucked in during the suction stroke of the engine passed through the cylindrical passageway defined by inner wall of this receptacle, thus drawing out the water through the porous inner wall and humidifying the air sucked in. The outer wall, also of porous material, and therefore humid, cleaned the air of dust during its passage therewith and before entering the passageway defined by the inner wall of the receptacle.

A primary object of the present invention is to provide a cleaning and humidifying construction which, on the one hand, shall more effectively clean and humidify than does the device of the aforescribed specification and which, on the other hand, realizes the above-enumerated desiderata.

To this end, briefly stated, the present invention provides a relationship of parts whereby the suction air is first passed through a filter which eliminates dust and other undesired foreign matter therefrom, and is then passed through a porous cylindrical passageway provided in a water reservoir to effect the desired atomization. An important feature of the invention is the embodiment of the said passageway in the form of a porous tube having an inlet which is smaller than the outlet thereof. Enhanced humidification, admixture of air and moisture, and atomization of the mixture are realized by developing the said tube as a Venturi nozzle.

A presently-preferred mode of carrying out the present invention is shown diagrammatically,

2

by way of example, on the accompanying sheet of drawing, the single figure of which represents a sectional view through the center of the device.

5 As shown on the said figure of drawing, the humidifier according to this invention may comprise a centrally-open hollow member 10 which with a central cylindrical element hereinafter described, defines a water or liquid receptacle or reservoir. This hollow member may conveniently be made of metal or of suitable plastic material such as Bakelite or the like. The reservoir may be filled by way of the filler tube 11 provided with cover 12. A conventional water level indicator may conveniently be provided, as at 13.

15 The top wall of reservoir 10 may be offset to provide a peripheral shoulder on which may be mounted a pair of spaced foraminous cylindrical walls 14 defining a cylindrical space therebetween. This space may be filled with a filter-forming material 15 such as copper filings, glass wool or the like. Peripheral bead 16 assists in retaining the resultant air-filtering unit in place.

20 Extending centrally through member 10 is the cylindrical nozzle member 17, the lower circumferential edge of which rests in a corresponding groove provided in the bottom wall of the reservoir. Member 17, or a portion thereof juxtaposed to the liquid in reservoir 10, may be made of a porous or water-permeable material, such as a ceramic or a textile or the like, which permits seepage and evaporation of the liquid contents of the reservoir.

25 The upper circumferential edge of nozzle member 17 is associated with flange member 18 mounted on and suitably secured to the top wall of the reservoir. Also mounted on and suitably fastened to the said top wall is the spider element 19, the upper end of which is suitably perforated to receive bolt 20. Cover member 21 closes the upper end of the entire device, including the filter unit, as shown, and is securely held in place with the aid of wing nut 22 in co-operation with bolt 20 which projects outwardly through the said cover member.

30 Means in the form of a flange member 23, suitably secured to the bottom wall of the reservoir, and a clamp and clamp-bolt assembly 24, are provided for associating the humidifier assembly with a conduit leading to the intake side of the carburetor. In this regard, the reservoir may be arranged anteriorly or posteriorly of the carburetor or in front of the suction opening of the engine.

Means in the form of a flange member 23, suitably secured to the bottom wall of the reservoir, and a clamp and clamp-bolt assembly 24, are provided for associating the humidifier assembly with a conduit leading to the intake side of the carburetor. In this regard, the reservoir may be arranged anteriorly or posteriorly of the carburetor or in front of the suction opening of the engine.

Air or the mixture of air and gas sucked in during the suction stroke of the internal combustion engine with which the device is associated, passes through filter element 14, 15 and is cleaned of its foreign ingredients in much more effective manner than is possible by mere contact with a damp surface. The air then passes downwardly through the central passage defined by nozzle member 17 and entrains from the surface of the latter the requisite quantity of moisture.

In the case of the device according to my aforesaid prior patent, the quantity of humidity withdrawn from the porous wall depends on the area of the surface of the said porous wall.

By constructing the member 17 with an inlet which is smaller than its outlet, i. e. by making it nozzle-shaped or by imparting a Venturi configuration thereto as shown, a jet effect is produced. The result is that, during the suction stroke of the engine, not only is a greater quantity of moisture entrained by the air per unit of area of porous nozzle material than has heretofore been possible, but also, through the increased velocity due to the jet effect, a better mixing of the sucked-in air and entrained water particles and also a better atomization of the mixture, are realized.

It is evident from the foregoing that the relationship of parts according to the present invention realizes the objects of the invention as above set forth.

It is to be understood that the specific embodiment above described in detail is purely exemplary in character and that the invention is not to be limited except as required by the terms of the claims hereunto appended.

Having thus described the invention, what I claim is:

1. A humidifier for the carbureter of an in-

ternal combustion engine comprising a multi-walled water reservoir including a substantially central inner wall defining a passageway there-through, an outer cylindrical wall spaced from and encompassing said central inner wall, and annular top and bottom walls extending between said inner and outer walls, said inner wall being constituted by a nozzle member of Venturi configuration and being porous whereby the contents of said reservoir may be drawn therethrough while the remainder of the walls are of non-porous material, said top wall being adapted to support means for filtering air, said passageway being provided with an inlet for filtered air at the 10 top thereof, and means interconnecting the other end of said passageway with the air inlet of the carbureter, the said Venturi configuration giving rise to a jet effect through said passageway, whereby enhanced entrainment of moisture from said reservoir through said inner wall and enhanced admixture of air and entrained moisture are realized.

2. A humidifier, as set forth in claim 1 the maximum cross-sectional area of said passageway being at its outlet end.

ANTOINE GAZDA.
